UNITED STATES PATENT OFFICE.

THOMAS WALTER PITCHER, OF BAYONNE, NEW JERSEY, ASSIGNOR TO RENTA WATER HEATER CO., A CORPORATION OF MAINE.

WATER-HEATER.

No. 895,584.

Specification of Letters Patent. Patented Aug. 11, 1908.

Application filed September 11, 1903. Serial No. 172,719.

To all whom it may concern:

Be it known that I, THOMAS WALTER PITCHER, a subject of the King of Great Britain, and a resident of Bayonne, New Jersey, 5 have invented certain new and useful Improvements in Water-Heaters, of which the following is a specification.

This invention relates to water heaters and more particularly to valve mechanism for 10 automatically controlling the fuel supply by the flow of water through the heater.

An object of the invention is to provide mechanism by which the fuel valve may be automatically controlled, and reliably so, by 15 the pressure of the water supplied to the heater, and more particularly to provide a mechanism which, though simple and compact, will operate reliably under a light water pressure.

It is also an object of the invention to provide an apparatus which is simple and cheap to construct and not apt to get out of order.

These and other objects of the invention will more fully appear from the following description.

The invention consists in the novel parts, improvements, and combinations herein shown and described.

The accompanying drawings, which are referred to herein and form a part hereof, illustrate one embodiment of the invention and serve in connection with the description herein to explain the principles thereof.

Of the drawings, Figure 1 is a vertical central section of a valve mechanism constructed in accordance with my invention, and Fig. 2 is a transverse section of the same taken on the line 2—2 of Fig. 1.

A valve mechanism constructed in accordance with my invention comprises a fuel controlling valve; a casing having water inlet and outlet passages; a fuel valve operating member arranged to establish communication between the inlet and outlet passages, 45 when in one position, and to interrupt said communication, when in another position; a fuel valve closing member subjected to water pressure on one side only and having an effective area as large as that of the valve opening member, said members being in axial alignment with each other; connections between said members and the fuel valve, said connections being such that the movement of the fuel valve opening member is greater 50 than the movement of the fuel valve closing

member for a given movement of the fuel valve.

In accordance with best embodiment of the invention, the fuel valve operating members are in the form of pistons operatively connected to each other as well as to the fuel valve.

In accordance with the particular embodiment of the invention illustrated, the casing of the device is made of two main parts 1 and 2, the part 1 being provided with a bore to receive the fuel valve opening piston 3, and the part 2 having a bore adapted to receive the fuel valve closing piston 4 and also a chamber in which the fuel valve 5 is located.

The members 1 and 2 of the casing are adjustably secured together in axial alignment as by means of a threaded section shown, a lock nut 6 being provided to secure the parts 75 in their adjustable positions. As shown, the part 1 of the casing is provided with a lateral boss 7, forming a water inlet passage, and with an extension or nipple 8, forming a water outlet passage. The piston 3, which is 80 preferably of inverted cup shape, is provided with one or more lateral openings 9 through which communication is established between the inlet and outlet passages, when the piston is moved a predetermined distance upwardly 85 in the bore of the part 1. A piston rod 10 is adjustably secured to the head of the piston 3 by any suitable means, as by the clamp nuts 11. As shown, the piston consists of a disk of suitable packing material, as leather, 90 which is clamped between a shoulder on a valve rod 12 and a nut 13 threaded on said rod.

The piston 4 preferably has an effective area which is at least equal to that of the piston 3, and suitable connections are provided between the pistons by means of which any movement imparted to the piston 3 by the water will be greater than the movement imparted to the piston 4. As shown, the connections consist of a plurality of levers 14 pivotally fulcrumed in the upper end of the part 2 and connected at their inner ends by suitable slots with the lower end of the piston rod 10. As shown, two of these levers are provided and they are symmetrically arranged on opposite sides of the axial line of the pistons in such manner that they will have no binding effect upon the pistons. The levers 14 are pivotally connected at intermediate 100 105 110

points to links 15, which are pivotally connected at their lower ends to the upper end of the valve rod 12. By reason of this construction a reduction in pressure on the upper surface of the piston 3 will cause an upward movement of both pistons notwithstanding that they are subject on their adjacent faces to the same water pressure acting in opposite directions. The valve rod 12 passes through a perforation in a diaphragm separating the chamber of the piston 4 from the chamber of the valve 5, a packing 16 being provided to prevent leakage of gas out of or water into the valve chamber. As shown, this packing consists of a conical ring of suitable packing material which is fitted to a correspondingly shaped recess in the diaphragm and is constantly forced upwardly into said recess in such manner as to keep the packing closely confined between the walls of the recess and the rod 12 by means of a washer 17 between which and the valve 5 a compression spring 18 is located. The diaphragm is preferably provided around the perforation for the rod 12 with an upwardly projecting lip 19, and the chamber of the piston 4 is preferably provided with a drain passage 20 which opens into said chamber at a point below the upper edge of said lip, thereby preventing such admission of water to the gas valve chamber as might be carried there by the reciprocating motion of the valve rod notwithstanding a sufficiently tight joint formed by the packing 16 to prevent the escape of gas. The seat for the gas valve 5 is preferably formed by the sharpened upper edge of the nipple 21, which is adjustably threaded into the lower end of the member 2 of the casing, the outlet passage for the gas being formed by a boss 22.

The operation of the device is as follows: The inlet passage of the valve being connected to the water main and the outlet passage to a water heater and the latter being filled with water, the pressure of the water acting upon the piston 4 will draw the piston 3 downwardly, the pressure on opposite sides of the piston 3 being balanced by means of a suitable restricted passage communicating with the space at the opposite sides of said pistons. This passage may be formed by a small perforation 23 in the upper part of the member 1 of the casing or by providing a sufficiently loose fit between the piston 3 and the chamber in which it is located. The lower surface of the piston 4 being in communication with the atmosphere through the drain passage 20, is urged downwardly by the full force of the water acting on its upper surface, and the fuel valve 5 will be forced to its seat by this pressure which will be sufficiently great, even under a very light water pressure, to reliably close the gas controlling valve. Whenever any water is drawn from the heater, however, the pressure on the up-

per surface of the piston 3 will be reduced, and by reason of the character of the connections between the piston 3 and the piston 4 said pistons will be moved upwardly by the unbalanced pressure of the water on piston 3, and thus open the fuel valve, the degree of the opening of the fuel valve being dependent upon the relative location of the opening 9 in the piston 3 and the top of the member 1 of the casing. This position may be varied by adjusting the piston 3 on the piston rod 10. The fuel valve will be held open as long as the flow of water through the heater is greater than can be supplied by the restricted passage 23 or its equivalent under a difference of pressure at its opposite ends sufficient to move the piston 3 in opposition to the force exerted by the piston 4. It will be seen that the compression spring 18 will serve to close the fuel valve, should the water pressure for any reason entirely fail, and thus prevent injury to the heater by overheating.

It will be seen that the device is simple and compact, the controlling force being obtained by pistons of small diameter as compared with the pistons heretofore used in similar devices. The parts being arranged in axial alignment, may be readily constructed of simple castings and when assembled will operate freely and are not apt to get out of adjustment.

My invention in its broader aspects is not limited to the precise construction shown nor to the particular construction by which it may be carried into effect, as many changes may be made in the details of the construction without departing from the main principles of the invention and without sacrificing its chief advantages.

Having thus described my invention, what I claim and desire to secure by Letters Patent is:

In an automatic valve mechanism, the combination with a fuel controlling valve, of a casing having water inlet and outlet passages and a piston chamber; a pair of pistons arranged in substantially axial alignment in said chambers, one piston being located between the inlet and outlet passages; connections between said pistons and the fuel valve, said connections including a plurality of levers symmetrically arranged with relation to the aligned axes of the pistons; a rod connecting one piston directly with the fuel valve; a diaphragm between the piston chamber and the valve chamber; a packing in said diaphragm; and a spring compressed between the packing and the fuel valve.

In testimony whereof, I have signed my name to this specification, in the presence of two subscribing witnesses.

THOMAS WALTER PITCHER.
